EP 0840878 6/2002

* cited by examiner

Primary Examiner — Catherine R Oliver-Garcia*(74) Attorney, Agent, or Firm* — Aaron R. Cramer; Cramer Patent & Design, PLLC(57) **CLAIM**

The ornamental design for a weapon concealment holster, as shown and described.

DESCRIPTION

FIG. 1 is a front, top and left side perspective view of a weapon concealment holster, showing my new design; FIG. 2 is a rear, top and right side perspective view thereof; FIG. 3 is a front elevation view thereof; FIG. 4 is a rear elevation view thereof; FIG. 5 is a left elevation view thereof; FIG. 6 is a right elevation view thereof; FIG. 7 is a top plan view thereof; and, FIG. 8 is a bottom plan view thereof.

The circular broken lines indicate the boundary region of an attachment device such as a rivet and form no part of the claimed design.

The rectangular broken lines indicate the boundary region of an attachment device such as hook-and-loop material and form no part of the claimed design.
